(57) **CLAIM**

The ornamental design for a necktie, as shown and described.

DESCRIPTION

FIG. 1 is a perspective view of the necktie;

FIG. 2 is a top view thereof;

FIG. 3 is a bottom view thereof;

FIG. 4 is a left side view;

FIG. 5 is a front view thereof;

FIG. 6 is a rear view thereof; and,

FIG. 7 is a top view of the necktie in a worn condition thereof.

The broken line showing of environment in FIG. 7 is for illustrative purposes only and forms no part of the claimed design.
